PROCESS OF FABRICATING LAMINATIONS

Ernest L. Furth, Pittsburgh, Pa., assignor to
Westinghouse Electric & Manufacturing Com-
pany, East Pittsburgh, Pa., a corporation of
Pennsylvania

Application December 13, 1935, Serial No. 54,251

6 Claims. (Cl. 29—155.5)

This invention relates to magnetic material and particularly to a continuous process of fabricating laminations of magnetic material for use in electrical apparatus.

5 In fabricating laminations of magnetic material for use in the cores of transformers or as rotor or stator punchings or other parts of electrical apparatus, the processes usually followed consist of a plurality of distinct and separate 10 steps requiring the handling of the laminations for each of the steps. In these processes, the expense of handling the material is large. It is also found that the strains set up in the material by handling are not uniform and that it 15 is not always possible to produce the same characteristics in a plurality of the laminations which have been subjected to similar heat treatments.

An object of this invention is to provide a continuous process for fabricating laminations of magnetic material suitable for building electrical apparatus.

This invention, together with other and additional objects, will be better understood from the following description, when taken in conjunction 25 with the accompanying drawing, in which

Figure 1 is a schematic plan view of the apparatus employed in the process of this invention.

Fig. 2 is a plan view of the strip material from 30 which the laminations are fabricated after it has been subjected to one of the steps of the process of this invention.

Fig. 3 is a plan view of the strip material after 35 it has been subjected to another step of the process in the fabricating of the laminations in accordance with this invention, and

Figs. 4 and 5 are plan views illustrating the strip material after it has been subjected to certain of the steps employed in fabricating a modified form of the laminations.

In fabricating the laminations of magnetic material for use in electrical apparatus, care must be exercised in order to protect the laminations from strains which have a detrimental effect on the magnetic properties of the material.

Referring to the drawing and particularly to Fig. 1 thereof, this invention is illustrated as applied to a continuous strip of magnetic material 10. In practice, the process of this invention is applied to the alloy comprising substantially 50% nickel, 50% iron with a small amount of manganese known by the trade under the trade mark "Hipernik" or a 4½% silicon steel known under the trade mark Hypersil. This

process is, however, applicable to any of the known magnetic steels.

As illustrated, the continuous strip 10 is drawn from a roll 11 of the magnetic material to an enameling chamber 12 containing a suitable enameling bath, such as water glass. In order to clean the surface of the strip before applying the enamel thereto, a set of brushes or rollers 13 are so disposed on the enameling chamber 12 that the strip 10 moves between the rollers 13 before entering the enameling bath. After the strip is coated with the enamel, the enamel may be dried either by exposure to the atmosphere or by means of the application of sufficient heat applied in any suitable manner. The enamel coating on the surface of the strip acts as an insulating coating and further acts as a lubricant for the cutting tools when the laminations are cut from the strip as hereinafter described.

Since the punching or cutting of the strip into 20 the desired shape and size of the laminations sets up strains in the material which are detrimental to its magnetic properties, this invention provides for so cutting the material along predetermined lines so as to substantially form 25 or outline the laminations prior to annealing the material.

As shown by Fig. 1 of the drawing, the enamelled strip 10 of the magnetic material moves from the enameling chamber 12 to a suitable 30 means for punching, cutting or severing the material along predetermined lines. As illustrated, the means comprises a punch press 14, the action of which may be controlled in any suitable manner by the speed or movement of the 35 continuous strip 10 as it passes through the punch press.

Fig. 2 of the drawing shows a portion of the strip 10 after it has been cut by the punch press 14. As shown, the shape of the laminations 15 has been outlined on the strip by cutting the strip along the predetermined lines 16 to substantially cut out the laminations. The laminations 15 are held in position in the strip 10 by the minor uncut portions 17 that are not 45 cut by the punch press 14. By cutting the strip in this manner, the laminations are partially severed from the strip and the strains of cutting the laminations are set up in the material before the material is annealed. The length and 50 number of the uncut portions or supports 17 will depend on the style and weight of the laminations 15. In addition to the cutting of the laminations along predetermined lines 16, the die of the punch press 14 cuts out or notches 55

a plurality of keyways 18 in the strip, the purpose of which will be explained hereinafter.

By retaining the substantially cut out laminations supported in position in the strip by the uncut portions 17, the laminations may be moved directly to the annealing furnace and subjected to a heat treatment to improve their magnetic properties and to release the strains set up by cutting the laminations.

10 In annealing the strip of magnetic material, the strip is subjected to a temperature of from 650° C. to 1200° C. The annealing cycle may be any of those known to the industry comprising a heating and predetermined cooling of the magnetic material. The cooling of the material may be accomplished either by moving the material through a cooling chamber (not shown) after it is annealed or where it is necessary to quickly quench the material, the quenching may be accomplished by moving the annealed strip directly into the air from the furnace 19 or the quenching may be accomplished by a suitable water or oil bath (not shown).

Where a controlled heating and cooling of the strip material is desired, the annealing furnace 19 may be so constructed that the temperature of the furnace may be controlled in a predetermined manner to provide predetermined annealing temperatures throughout the length of the furnace. This annealing develops the magnetic properties of the material and releases the strains set up in the laminations when cut or punched by the punch press 14.

After being annealed, the strip material 10 with the laminations supported in position therein is drawn from the annealing furnace 19 to a second enameling chamber 20 containing a bath of water glass or other suitable enameling liquid. As on the device shown generally at 12, brushes 21 are provided on the enameling chamber 20 to clean the strip material before it enters the enameling bath.

When the strip material is annealed to develop its magnetic properties and anealed to provide insulation, it moves to a punch press 22 for cutting or severing the points of support 17 of the laminations 15 held in position in the strip material 10. The punch press 22 is similar to the punch press 14, and is similarly controlled by the speed or movement of the strip 10. The punch press 22 is so set that when the keyway 18 cut into the strip 10 by the punch press 14 is fitted therewith, it operates to cut the strip material, as shown in Fig. 3, along the predetermined lines 23 to cut the points of support 17 and sever the laminations 15 from the strip.

The strains set up in the laminations by severing the laminations 15 from the strip material are negligible. This is because only a negligible portion of the material is affected when the portions supporting the laminations in the strip are cut.

In moving from the punch press 22, the laminations 15 are removed from the continuous strip of material 10 by any suitable means and the strip of scrap material remaining may be wound into the roll 26.

This invention may be employed in fabricating laminations other than those suitable for use as the core parts of transformers. Figs. 4 and 5 of the drawing show the strip 10 after it is subjected to the cutting steps before and after the anneal respectively in fabricating a rotor punching. As illustrated, the rotor punching 27 is substantially cut out along predetermined lines 28

by the action of the punch press 14 prior to the annealing step. The rotor punching 27 is supported in position in the strip by the uncut supporting portions 29. After annealing and enameling the substantially cut out rotor punching 27, the finished punching may be completely severed from the strip 10 by cutting the strip 10 along predetermined lines 30 to cut the points of support 29 when the strip is drawn through the punch press 22.

By the process of this invention, it is evident that laminations of magnetic material suitable for building electrical apparatus may be fabricated without handling the material between each of the steps of cutting the laminations and annealing and enameling. Further, it is evident that each of the laminations receives the same treatment throughout the process so that the characteristics developed in the material will be uniform.

Although this invention has been described with reference to a particular process, it is evident that other and various modifications thereof are possible. Instead of the punch presses 14 and 22, described in this particular process, shears, slitters 25 or simple tools for forming the cutting punches may be substituted. Further, although this invention has been described with reference to cutting particular designs of laminations along certain predetermined lines, it will be understood 30 that other and various forms of the laminations may be fabricated. Where desired the enameling steps may be eliminated. This invention is, therefore, not to be restricted except insofar as is necessitated by the prior art and the scope of the 35 appended claims.

I claim as my invention:

1. In a continuous process of fabricating laminations for electrical apparatus from a continuous strip of magnetic material, in combination, 40 moving the strip through an enameling bath to provide an insulating coating on it, moving the insulated strip through means for cutting the strip along predetermined lines to substantially form the laminations, the laminations being 45 maintained in position in the strip by predetermined uncut supporting portions, moving the strip through a furnace at a temperature sufficiently high to anneal it and moving the annealed strip through another means for cutting the said supporting portions to sever the annealed and insulated laminations from the strip. 50

2. In a continuous process of fabricating laminations for electrical apparatus from a continuous strip of magnetic material, in combination, 55 moving the strip through an enameling bath to provide an insulating coating on it, moving the insulated strip through means for cutting the strip along predetermined lines to substantially form the laminations, the laminations being 60 maintained in position in the strip by predetermined uncut supporting portions, moving the strip through a furnace at a temperature sufficiently high to anneal it, moving the annealed strip through another enameling bath to further 65 insulate the strip material, and moving the annealed and insulated strip through another means for cutting the said supporting portions to sever the annealed and insulated laminations from the strip. 70

3. In a continuous process of fabricating laminations for electrical apparatus from a continuous strip of magnetic material, in combination, moving the strip through means for cutting the strip along predetermined lines to substantially 75

form the laminations, the laminations being maintained in position in the strip by predetermined uncut supporting portions, moving the strip through a furnace at a temperature sufficiently high to anneal the strip, moving the annealed strip through an enameling bath to provide an insulating coating for the laminations, and moving the annealed and enameled strip through another of said means for cutting the said supporting portions to sever the annealed laminations from the strip.

4. In a continuous process of fabricating laminations for electrical apparatus from a continuous strip of magnetic material, in combination, moving the strip through an enameling bath to provide an insulating coating on it, moving the insulated strip through a punch press and operating the punch press to outline the shape of the laminations and partially sever them from the strip, moving the partially severed strip through a furnace to anneal the material, and then moving the partially severed and annealed strip of material through another punch press to complete the severing of the laminations from the annealed strip of material.

5. In a continuous process of fabricating laminations for electrical apparatus from a continuous strip of magnetic material, in combination, passing the strip through an enameling bath to

provide an insulating coating on it, passing the insulated strip through means for outlining the shape of the laminations and partially severing them from the strip, passing the partially severed strip through a furnace to subject the strip to a temperature of between 650° C. and 1200° C., cooling the strip, and then passing the partially severed and heat-treated strip of material through another means to complete the severing of the laminations from the strip of material.

6. In a continuous process of fabricating laminations for electrical apparatus from a continuous strip of magnetic material, in combination, passing the strip through an enameling bath to provide an insulating coating on it, passing the insulated strip through means for outlining the shape of the laminations and partially severing them from the strip, passing the partially severed strip through a furnace to subject the strip to a temperature of between 650° C. and 1200° C., cooling the strip, passing the heat-treated strip of material through another enameling bath to further insulate the strip material, and then passing the partially severed, heat-treated and insulated strip of material through another means to complete the severing of the laminations from the strip of material.
